FEEDING AND UNLOADING DEVICE FOR
WEIGHING OR CHECKING APPARATUS
FOR CIGARETTES

Rudolf Fellmann, Prague-Smichov, Czechoslovakia, assignor to Skoda Works, National Corporation, Pizen, Czechoslovakia

Application January 28, 1948, Serial No. 4,918

Claims priority, application Czechoslovakia
February 21, 1947

1 Claim. (Cl. 198—39)

1

My invention relates to weighing or checking apparatus for cigarettes and more particularly to feeding and unloading devices used in combination therewith.

The main object of my invention is to avoid the disadvantages of the known devices of that type which are intricate in construction and not always reliable in operation. My new device may be used to weigh and to check either individual cigarettes coming from a cigarette making machine or groups of such cigarettes.

The said and other objects of my invention will be more fully understood from the following specification when read with the accompanying drawing in which one embodiment is illustrated by way of example.

In the drawing:

Figs. 1 and 2 show in front view and in side view, respectively, partly in section, a conveyor device for cigarettes coming from any conventional cigarette making machine, and a device for lifting individual cigarettes from said conveyor device in timely intervals.

Fig. 3 shows in front view structural members of my new feeding and unloading device cooperating with said lifting device and with a weighing or checking apparatus for cigarettes.

Fig. 4 shows a side view thereof including driving means therefor.

Fig. 5 shows in front view the structural members illustrated in Fig. 3 in another position, and cam means to operate said members, and

Fig. 6 shows in front view the same structural members in still another operative position.

The same reference numbers indicate the same parts in all figures of the drawing.

The conveyor device illustrated in Figs. 1 and 2 is adapted to cooperate with a conventional cigarette making machine which is not shown in the drawing and comprises a continuously rotating grooved drum or the like 1 which receives the cigarettes 2 from the cigarette making machine and transfers the same in parallel-axial positions upon a continuously driven conveyor belt 3 supported by a plurality of rollers 4 (only one being shown in the drawing) which rest in bearings 5, 6, mounted in the apparatus frame 7. The drum 1 and the rollers 4 turn anti-clockwise as indicated by the arrows shown in Fig. 2 and they are driven in any convenient known manner.

From the stream of parallel-axial cigarettes moving on and with the conveyor belt 3 one cigarette is seized at intervals and lifted out of the stream by a device of which many are known in the art. In the shown embodiment (Figs. 1 and 2) said device comprises a pair of automatically controlled cooperating grasping jaws 14, 15 which while rotating with the shaft 80

2

10 seize a cigarette 2 from the said stream of cigarettes and lift the same above, and release the same into the receiving bed 29 of a cam controlled rocking lever 28. The said shaft 10 is of square cross section, is rotatably mounted in bearings 8, 9 supported in the frame 7, and is continuously rotated by a pulley 11 driven by a belt 13 from an electric motor not shown in the drawing. The jaws 14, 15 are slidably mounted upon the shaft 10 and are provided at their outer ends with flat springs 16 and 17, respectively, to hold the cigarettes 2 resiliently therebetween. The jaws 14, 15 are actuated that is moved into the seizing position illustrated in full lines in Fig. 1 and into the releasing position shown therein in dotted lines by an eccentrically suspended pendulous disclike weight 20 which is mounted in a longitudinal slit 18 of the shaft 10 and is swingably held therein by a pivot 19. Said pendulous weight 20 is linked to the jaws 14, 15 by connecting rods 22 and 23, respectively, which rods are jointed with their ends 24, 25 and 26, 27 to said jaws 14, 15 and to the weight 20, respectively.

25 This weight 20 in the position shown in Fig. 1 in full lines holds the jaws 14, 15 in grasping position to seize one of the cigarettes 2 carried by the belt 3. The jaws 14, 15 revolving with the continuously turning shaft 10 lift the seized cigarette above the receiving bed 29 of the conveying lever 28. During that time the weight 20 while turning with the shaft 10 slides along a guide member 21 and is prevented to swing about its pivot 19; thus the jaws 14, 15 remain in seizing position retaining the cigarette 2 between said springs 16, 17. After a revolution of 180° the said weight 20 reaches the position shown in dotted lines in Fig. 1 and is thereafter released by said guide member 21 to swing downward in clockwise direction thereby distancing the jaws 14, 15 from each other and releasing the lifted cigarette into the bed 29 of the rocking lever 28. After an additional turn of 180° the distanced jaws 14, 15 are again returned by the weight 20 into their operative seizing position illustrated in Fig. 1.

50 The said shaft 10 drives through the gears 12 and 32 with the same number of revolutions a shaft 31 which rests in bearings 33, 34 and which carries cam discs 35, 36 (Figs. 4 and 5). Another shaft 39 resting in bearings 37, 38 carries keyed thereupon the rocking conveying lever 28 mentioned above and an operating arm 40 thereof having a guide roller 41 sliding upon the cam disc 35 (Figs. 4 and 5). Still another shaft 44 resting in the bearings 42, 43 is actuated by the arm 48 having a guide roller 49 sliding upon the cam disc 36 and said shaft 44 has keyed thereupon a forked auxiliary lever 45 provided at its swinging end with an outer bed 46 and an inner bed 47 each bed being

adapted to receive a cigarette. The said bearings 33, 34, 37, 38, 42, and 43 are all mounted in the machine frame 7 referred to above. The rocking lever 28 and the auxiliary lever 45 are actuated by their respective cams 35, 36, in a timely overlapping relation with each other and with the forked scale pan 51 which is attached by a suspension member 52 to one end of the double armed scale beam 50, the other end thereof supporting an adjustable counterweight 54. The said scale beam 50 oscillates about the fulcrum 53 and is provided with an indicator arm 55 cooperating with a scale 56. The swing movement of the scale beam 50 is limited by stop members 57, 58. Below the lowermost position of the scale pan 51 is an inclined stationary flap or similar member 59 which is situated to avoid the arms of the forked auxiliary swing lever 45 (Figs. 3 and 4).

In the shown embodiment the length of the scale beam arm supporting the scale pan 51 is equal to the length of the auxiliary lever 45 between its fulcrum 44 and the outer bed 46. Likewise the distance between the scale beam fulcrum 53 and the fulcrum 58 of the auxiliary lever 45 is equal to the length of the suspension member 52 for the scale pan 51. In view of this parallelogrammatic arrangement the path of the bed 46 and the path of the scale pan 51 will coincide.

My new device will operate as follows:

The cigarettes 2 coming from a cigarette making machine are transported in parallel positions transversely to their axis upon a conveyor belt supported by a plurality of rolls 4. From this stream of cigarettes one cigarette is seized at intervals by the automatically controlled grasping jaws 14, 15, lifted as shown in Figs. 1 and 2 above a receiving bed 29 in a cam controlled conveying lever 28 and thereafter released thereupon. While one cigarette is weighed upon the forked scale pan 51 which suspends from the scale beam 50, the said conveying lever 28 swings towards the weighing device and at the same time the cam controlled auxiliary lever 45 swings upwards from its lower position shown in Fig. 3. The auxiliary lever 45 which is also forked meshes in a comb-like manner with the forked scale pan 51 and with the forked end of the conveying lever 28 as recognizable from Fig. 4. At the swinging end of the auxiliary lever 45 is an outer bed 46 arranged to receive and to support a cigarette. The middle portion of the path of the up and down swinging bed 46 coincides with the limited up and down movement of the scale pan 51 so that the said auxiliary lever 45 while moving upwards lifts the cigarette being weighed upon the scale pan 51 as shown in Fig. 6. Meanwhile the conveying lever 28 swings near to the weighing device and the steering face 30 on said lever 28 pushes the cigarette resting in the outer bed 46 into a parallel inner bed 47, thus freeing the said outer bed 46 to receive and to lift the cigarette transported by the conveying lever 28 towards the weighing device (Fig. 5). Thereafter the cam controlled levers 28 and 45 start their return movement into the positions shown in Fig. 3. The rocking lever 28 after its return to the starting position shown in Figures 1, 2 and 3 receives another cigarette lifted from the conveyor belt. While the auxiliary lever 45 returns from the position shown in Fig. 5 into the position shown in Fig. 3 the cigarette now resting in the outer bed 46 is transferred to the scale pan 51 to be weighed,

whereas the previously weighed cigarette now resting in the inner bed 47 is transported downwards towards an inclined flap 59 or similar member to be lifted thereby from the inner bed 47 and freed for further transportation.

While in the described and shown embodiment of my invention cigarettes are individually withdrawn from a stream of cigarettes and weighed thereafter, it will be well understood that without departing from my invention two or more cigarettes may be simultaneously withdrawn as a group from the stream of cigarettes and thereafter weighed upon a weighing device. In such case it is only necessary to adapt the seizing device, the conveying lever 28, the beds 46 and 47 upon the auxiliary lever 45 and the scale pan 51 to hold more than one cigarette at a time.

Although only one embodiment of my invention has been shown and described by way of illustration, it will be understood that my invention may be constructed in various other embodiments which will come within the scope of the appended claim.

What I claim as my invention is:

- 25 In combination with a weighing or checking apparatus for cigarettes including a balance beam, stops limiting the swing movement thereof, and a forked scale pan attached thereto and adapted to receive a cigarette; a feeding and 30 unloading device comprising means to automatically lift at intervals a cigarette from a stream of parallel axial cigarettes and to release the lifted cigarette, a cam controlled rocking conveying lever adapted to receive at its swinging end 35 said released cigarette, an auxiliary lever cooperating with its up and down swinging end in overlapping relation with the swinging end of said conveying lever and with said scale pan, an outer bed and an inner bed upon the swinging end of 40 said auxiliary lever, each bed adapted to support a cigarette in a position parallel to that of the scale pan supported cigarette, the path of the up and down swinging outer bed coinciding in its middle portion with the limited path of the scale 45 pan between its loaded lower position and its unloaded upper position so that each cigarette after being weighed is lifted from the scale pan by the upswinging outer bed, a camming face on the swinging end of the conveying lever to push the lifted weighed cigarette from said outer bed into said inner bed, thus freeing the outer bed to lift the next cigarette from the conveying lever and permitting the outer bed to transfer said next cigarette upon the scale pan on the 50 following downward movement of the auxiliary lever, means to remove the weighed cigarette from the inner bed at the end of the downward movement of the auxiliary lever, and driving means to swing the conveying lever and the auxiliary lever in timely relation.

RUDOLF FELLMANN.
